UNITED STATES PATENT OFFICE.

JOHN Y. BASSELL AND FRED C. BLENKNER, OF COLUMBUS, OHIO.

SIGHT-PIECE.

No. 807,710.

Specification of Letters Patent.

Patented Dec. 19, 1905.

Application filed May 13, 1904. Serial No. 207,779.

To all whom it may concern:

Be it known that we, JOHN Y. BASSELL and FRED C. BLENKNER, citizens of the United States, residing at Columbus, in the county of 5 Franklin and State of Ohio, have invented a certain new and useful Improvement in Sight-Pieces, of which the following is a specification.

Our invention relates to a new and useful improvement in gun-sight pieces.

10 The object of the invention is to provide a superior sight-piece in which the sight-center is supported within a ring which when used in connection with a globe so concentrates the aim as to insure great accuracy.

15 Finally, the object of the invention is to provide a device of the character described that will be strong, durable, and efficient and one which will be simple and comparatively inexpensive to make.

20 With the above and other objects in view the invention consists of the novel details of construction and operation, a preferable embodiment of which is described in the specification and illustrated in the drawings,

25 wherein—
Figure 1 is a front elevation of one of the sight-pieces. Fig. 2 is a front elevation of a modified form having the cross-line center. Fig. 3 is a front elevation of still another 30 form employing the cross-center. Fig. 4 is a front elevation of a globe, showing the sight-piece illustrated in Fig. 1 supported therein; and Fig. 5 is a side elevation of one of the sight-pieces.

35 It is to be understood that the essential feature of the invention resides in a ring 1, which is suitably supported by any means, although we prefer to use a stem 2. Various forms of centers may be supported within the 40 ring. In Fig. 1 we have shown what is commonly known as the "ball-center" 3, and it will be readily apparent that the centering of the aim on the ball 3 is greatly facilitated by the ring 1, which when supported in the 45 globe 4 readily attracts the eye and enables the gunner to easily get a line on the bull's-eye of the target.

In Fig. 2 we have shown cross-lines 5, supported within the ring 1, which is preferable 50 in some instances, and in Fig. 3 we have

shown at 6 a cross-center supported within the ring 1, by the addition of which ring the value of the center is greatly increased.

These sight-pieces may be formed with any suitable form of base by which they are supported in the globe, so that they may be readily interchanged, so that different forms of sight-pieces may be used for various kinds of shooting. It is within the scope of our invention to illuminate the sight-centers, so as 55 to contrast them with the surrounding parts; but the sight-center may be formed in any suitable manner, according to the purpose for which it is employed.

It will be observed that by employing the 60 ring 1 the same greatly aids in aiming the arm, as where ringed targets are used the ring 1 will conform to the rings on the target and facilitate the alining of the center with the bull's-eye. Thus a gunner is enabled to 65 draw the finest bead, and the aim is concentrated from the ring to the sight-center and any slight deviation will be readily discernible.

We do not wish to limit ourselves to the 70 exact details of construction and operation herein set forth, as we may make various changes in the same without departing from the spirit of our invention.

Having now fully described our invention, 75 what we claim, and desire to secure by Letters Patent, is—

1. A sight-piece adapted for use in conjunction with a globe-sight comprising a ring adapted to be disposed concentric with the 80 globe-center, but having a smaller diameter than the globe so as to provide a substantial space therebetween, and a sight-center supported from the ring.

2. A sight-piece adapted for use in conjunction with a sight-cylinder comprising a ring adapted to be disposed within and concentric with the cylinder so as to provide an annular interspace therebetween, and a sight-center supported within the ring.

JOHN Y. BASSELL.

FRED C. BLENKNER.

In presence of—

M. B. SCHLEY,
A. L. PHELPS.
